UNITED STATES PATENT OFFICE.

JOHN W. NICHOLS, OF LOS ANGELES, CALIFORNIA.

HEADLIGHT.

1,332,139.

Specification of Letters Patent. Patented Feb. 24, 1920.

Application filed June 16, 1919. Serial No. 304,622.

To all whom it may concern:

Be it known that I, JOHN W. NICHOLS, a citizen of the United States, residing at Los Angeles, in the county of Los Angeles and State of California, have invented new and useful Improvements in Headlights, of which the following is a specification.

This invention relates to a headlight and pertains particularly to means for distributing the projected light.

It is desirable in headlights for vehicles to so distribute the light over the field to be illuminated that the intensity is greatest in the immediate path of travel and less intense over the field adjacent thereto. Another desideratum is that of so projecting the light that pedestrians, drivers and others in the roadway will not be blinded by the glare of the light. It is the principal object of this invention to provide means to accomplish the above mentioned results.

These objects will be more fully understood, as will also other objects and corresponding accomplishments of my invention from the following detailed description of a preferred embodiment thereof. For the purpose of this description reference is had to the accompanying drawing, in which:

Figure 1 is a vertical section through a headlight; Fig. 2 is a view looking in the direction of the arrows 2-2 of Fig. 1; Fig. 3 is a section taken on the line 3-3 of Fig. 1; and Fig. 4 is a plan view of the headlight.

Referring more particularly to the drawing, a lamp casing is indicated by 5. This casing is preferably metallic and polished upon its inner surface so as to produce a mirror finish. Extending through the rear of the casing is a lamp socket 6 for supporting a lamp 7. A glass lining 8 is preferably disposed within the lamp casing.

The invention resides particularly in the lamp casing and especially in its form. The rear of the lamp casing comprising the reflector proper is preferably of parabolic form. An opening 10 is formed therein, through which the lamp socket 6 extends. The casing extends forwardly from the reflector portion to form a tunnel having divergent side walls 11 and 12 and flat parallel or substantially parallel top and bottom walls 14 and 15. The tunnel is thus of general funnel shape with the small end hav-

ing the lamp 7 disposed thereon. By referring to Fig. 1 it will be noted that the lip 55 of the top wall 14 overhangs the lip of the bottom wall 15 at the mouth.

Light is projected forwardly by the reflector portion 9, those rays which do not impinge upon the funnel wall issuing at the 60 forward end and spreading in fan form horizontally. There will of course, be some rays which will impinge upon the side walls and be reflected therefrom to the sides, producing a field of illumination of less intensity than the central field. The top wall 14 prevents the projection upwardly above the line of vision of pedestrians of any directly reflected rays from the lamp. In order to still further cut down the intensity of any 70 illumination in the line of vision, the bottom wall 15 is overlapped by the top wall. Thus, the overhang of the top wall shuts out certain of the rays reflected from the bottom wall.

The glass liner 8 conforms to the shape of the lamp casing. However, this element forms no part of my invention, although advantageous for certain purposes.

It is obvious that I have provided a headlight which will project rays forwardly confining the direct projected rays, which are of greatest intensity, to a wide horizontal fan shape of small height; in addition to this there is a gentle illumination to the sides of 85 the central field, this illumination being secured by indirect reflection. Furthermore, a very important factor is the illumination in the line of vision of pedestrians, this being still less in intensity than the side 90 illumination.

What I claim is:

A headlight comprising in combination, a casing provided with a concave reflector and an extension having substantially flat top 95 and bottom walls for passage of the light rays therethrough, the walls of said extension merging with said reflector and having an upper lip overhanging the lower lip thereof, and a light disposed at the rear of 100 said casing in front of said reflector so that the rays will be projected forwardly.

In witness that I claim the foregoing I have hereunto subscribed my name this 9th day of June, 1919.

JOHN W. NICHOLS.
